UNITED STATES PATENT OFFICE.

LEWIS M. CURRY, OF CHICAGO, ILLINOIS.

ADJUSTABLE JAMB-HINGE.

SPECIFICATION forming part of Letters Patent No. 609,756, dated August 23, 1898.

Application filed August 2, 1897. Serial No. 646,770. (No model.)

To all whom it may concern:

Be it known that I, LEWIS M. CURRY, a citizen of the United States, residing at Chicago, in the county of Cook and State of Illinois, 5 have invented certain new and useful Improvements in Adjustable Jamb-Hinges; and I do hereby declare the following to be a full, clear, and exact description of the invention, such as will enable others skilled in the art to

o which it appertains to make and use the same.

This invention relates to an adjustable hinge attachment for door-jams, and has for its object to provide a device of this character whereby the swelling or shrinking of a 5 door and jamb may be conveniently compensated for and the parts accurately adjusted with reference to each other.

In the drawings, Figure 1 is a view in perspective of a hinge embodying the improvement; Fig. 2, a detached perspective of a socket-piece; and Fig. 3, a broken-away horizontal section on line 3, Fig. 1, looking in the direction indicated by the arrow.

A represents an ordinary door-hinge; A', 5 the door; B, an adjustable jamb; C C', the jamb-lining, and D a stud.

A plate E is located on the inner side of the jamb and is secured rigidly in place by a number of screws a, inserted through the 5 leaf a' of the door-hinge and the jamb and ending in the plate. The plate E is provided on the outer side with a stop projection a², which holds the hinge and plate some distance apart and extends through the jamb. 15 A guide projection a³ is formed on the opposite side of the plate E.

A socket-piece F, provided with a lug a⁴, is seated in the stud D and secured in place by screws a⁵, passing through the lug a⁴, as 15 shown in Fig. 3. The projection a³ is inserted loosely in the chamber b of the socket-piece F and is adapted to have an endwise movement therein.

The stop projection a² and the guide projection a³ have a passage b' extending longitudinally therethrough for the reception of the adjusting-screw H, the inner end of which has a threaded engagement with the thick-

ened bottom part d' of the socket-piece F. The head d' of the adjusting-screw bears 50 against the inner side of hinge-leaf a' and is provided with the screw-driver slot g, which is reached through an aperture h in the hinge-leaf and which is of a less diameter than the head of the adjusting-screw, so that the latter is adapted to have a rotary but not a longitudinal movement. 55

Now, as the proper relative position of the door and jamb is affected by atmospheric changes, the parts may be adjusted by turning the adjusting-screw in one direction or the other, as the case may require. Turning the adjusting-screw to the right draws the movable jamb inwardly, the guide projection a³ moving in the same direction in 65 the socket-piece F. Turning the adjusting-screw to the left moves the parts in the opposite direction.

It will be understood, of course, that each of the hinges connecting the door may be 70 provided with the adjusting device and that but a slight movement of the adjustable parts is sufficient for the purpose of maintaining the required relative position.

Having thus described my invention, what 75 I claim as new, and desire to secure by Letters Patent, is—

The combination with a door or other object, of a movable jamb, a hinge, a plate, secured to one leaf of the hinge and located on 80 the inner side of the jamb and having a stop projection extending therethrough, and a guide projection extending in the opposite direction, a socket-piece, secured rigidly in place and with which said guide projection 85 has a movable engagement, and an adjusting-screw, inserted longitudinally through said plate and projections and having a threaded engagement with said socket-piece, substantially as described. 90

In testimony whereof I affix my signature in presence of two witnesses.

LEWIS M. CURRY.
